United States Patent Office

Des. 178,733

Patented Sept. 11, 1956

178,733

JEWELRY CHAIN

Walter F. Morris, Providence, R. I.

Application February 16, 1955, Serial No. 34,539

Term of patent 7 years

(Cl. D45—16)

FIG. 1

FIG. 2

FIG. 3

Fig. 1 is a plan view of one of the individual links of the chain embodying my new design, drawn on an enlarged scale.

Fig. 2 is an edge view of the same.

Fig. 3 is a plan view of a segment of chain made with the link shown in Fig. 1.

I claim:

The ornamental design for a jewelry chain, as shown.
